UNITED STATES PATENT OFFICE.

EMILE SINS, OF PARIS, FRANCE, ASSIGNOR TO CHENEY BROTHERS, A CORPORATION OF CONNECTICUT.

DESIGN FOR A TEXTILE FABRIC.

No. 39,225.

Specification for Design.

Patented March 24, 1908.

Application filed January 20, 1908. Serial No. 411,849. Term of patent 3½ years.

To all whom it may concern:

Be it known that I, EMILE SINS, a citizen of the French Republic, residing at the city of Paris, in the Republic of France, have invented a new, original, and ornamental Design for Textile Fabrics, of which the following is a specification, reference being had to the accompanying drawing, forming part thereof.

The figure is a plan view of the fabric, showing my new design.

I claim:

The ornamental design for a textile fabric, as shown.

E. SINS.
